CLAIM

The ornamental design for an ice cream cooler, as shown and described.

DESCRIPTION

FIG. 1 is a front perspective view of an ice cream cooler showing my new design;

FIG. 2 is a front view thereof;

FIG. 3 is a back view thereof; with the right side and left side being identical;

FIG. 4 is a top view thereof;

FIG. 5 is a bottom view thereof; and,

FIG. 6 is a cross-sectional view taken along line 6-6 of FIG. 4.

In FIG. 5 the dash-dash broken lines are for the purpose of illustrating portions of the ice cream cooler that form no part of the claimed design.

1 Claim, 4 Drawing Sheets
